UNITED STATES PATENT OFFICE.

JOAQUIN FERNANDEZ SILVA, OF CENTRAL LUTGARDITA, CUBA.

APPARATUS FOR UNLOADING RAILROAD-CARS.

1,268,504.

Specification of Letters Patent.

Patented June 4, 1918.

Application filed July 20, 1917. Serial No. 181,802.

To all whom it may concern:

Be it known that I, JOAQUIN FERNANDEZ SILVA, a citizen of the Republic of Cuba, and a resident of Central Lutgardita, Province 5 of Santa Clara, Cuba, have invented certain new and useful Improvements in an Apparatus for Unloading Railroad-Cars, of which the following is a specification.

This invention relates to an apparatus for 10 unloading railroad cars, and particularly to an apparatus whereby goods in bulk can be removed from the interior of box cars and other cars without necessitating the arrangement of movable platforms or the like on 15 which the entire cars must be hoisted.

While the apparatus has been primarily designed for use in sugar mills, to transfer sugar cane, or other raw material arriving from the plantation, to a carrier on which 20 this material may be conveyed to the plant itself, it is obvious that the apparatus may also be installed and used in other establishments.

An object of the invention is to provide 25 an apparatus, comprising a stationary inclined platform and means disposed adjacent to this platform for maintaining a car on said platform under an angle at which the discharge of the contents of the car may 30 readily be effected.

Another object of the invention is to combine with a device for retaining the car under a maximum discharge angle means for moving this retaining device together 35 with the car, so as to guard the car against turning over.

Another object of the invention is to provide in combination with the inclined unloading platform a track for a retaining device 40 adapted to support the retaining device and to hold this support against lateral displacement over the entire length of the platform.

In an actual installation of this apparatus 45 the unloading operation for a number of cars, aggregating in their contents several hundred thousand pounds of raw material, has been effected per day by two workmen only. Prior to this installation the expense 50 for unloading the same kind and volume of material amounted to more than \$32 per day. It should also be noted that the installation of the apparatus can readily be carried out by any of the modern plants for 55 treating large quantities of raw or half

finished material, as most of these plants are necessarily located near railroad tracks, and as the apparatus merely involves the modification of certain portions of the switch yard or spur track, which in plants 60 of this character is connected with the main road.

Other objects of the invention will be more fully understood from the following specification, reference being had to the accompanying drawing, wherein:

Figure 1 is a front elevation of the apparatus, including the unloading platform and the retaining device with its supports,

Fig. 2 is a rear view of the same,

Fig. 3 is a sectional view, partly in elevation, on the line A—B of Fig. 1, the car being shown in dotted lines,

Fig. 4 is a front elevation of one of the retaining trucks,

Fig. 5 is a rear elevation of the same,

Fig. 6 shows, partly in elevation and partly in section, a detail of one of the attachment hooks for the chains,

Fig. 7 shows, in elevation, one of the 80 brackets whereby several of the rails for the retaining devices are supported,

Fig. 8 is a sectional view through the same on line C—D of Fig. 7, and

Fig. 9 is a sectional view on line A—F 85 of Fig. 6 to illustrate the cross-section of the hook.

Referring to the drawings, it will be seen that the invention comprises an inclined surface or platform 1, on which rails 2 and 3 90 are mounted, the distance between these rails corresponding to the standard gage or to the gage of that railroad system on which the plant is located.

The inclination of the unloading surface 95 1 with respect to the plane or straight surface on which the ordinary track (not shown) is laid, naturally varies in different portions of said surface. The surface rises from the level of the track at one end and 100 gradually ascends from this end until it reaches a maximum angle of inclination, which is illustrated in Fig. 3, and from this portion of the platform having the maximum angle of inclination the angle gradually recedes again until at the other end of the unloading platform this platform or surface merges into the plane on which the ordinary track is laid. The maximum grade 105 of ascension and unloading angle may de- 110

pend upon the character of the goods and upon the weight of the loaded cars to be handled.

Hence the unloading platform may be described as consisting of three portions: an ascending portion gradually rising from the level of the track, not only in longitudinal direction, but also in lateral direction; an unloading portion on which the axis of the track is parallel to the axis of the level track of the railroad system, while a relatively steep grade is present, measuring transversely to the tracks of the ordinary railroad system; and a descending portion generally resembling the ascending portion and effecting the gradual approach from the unloading portion to the level of the ordinary track. From this description it will be understood that the unloading platform in its entirety is not a straight plane, but is a surface in which certain portions are askew with respect to each other. The three portions of the unloading platform described (the middle portion only being shown) may have equal length, so that the unloading portion proper occupies the central third of the entire platform, measured longitudinally.

Adjacent to the running rails 3 is placed another rail 4, which, as may be seen from Fig. 3, serves for engaging the wheel flanges of a car placed on the platform, and which assists in this manner in maintaining the car at the proper unloading angle.

Near the unloading or middle portion of the platform 1 and close to the upper end of said portion, another, horizontal, platform 5 is mounted, which may be supported on pillars 6 of concrete, or of any other suitable material. These pillars, as shown in Fig. 3 of the drawing, consist of slabs of concrete or the like extending transversely underneath the horizontal platform 5 and provided with suitable passages to facilitate the inspection of the lower surface of the horizontal platform and repairs when required. It is obvious, however, that any other suitable support for the horizontal platform may be selected.

Uprights 7 and 8 project from portions of the horizontal platform 5 near the ends of the same and serve for supporting the ends of a plurality of rails 9, 10, 11, and 12, which are disposed, horizontally and hence parallel to each other, in pairs, the upper rails 9 and 10 having their heads directed toward each other and the lower rails 11 and 12 also having their heads directed toward each other, while the central rails 10 and 11, as may be seen from Fig. 3, have their foot plates closely adjacent and directed toward each other. The upper rail 9, which may be secured at its ends to the uprights 7 and 8 in any desirable way, as, for instance, by spikes (not shown in the drawing), is also supported intermediate its

ends and near its ends by additional uprights 13, 14, 15, 16, and 17. These intermediary and end posts 13 to 17 consist, as may be seen from Fig. 3, of an upper horizontal arm, to the lower face of which the foot of the rail 9 is secured, and of a lower horizontal arm secured to the platform 5 by spikes 18 and 19, the two horizontal arms of each upright being interconnected by an inclined portion. 75

The rigidity of the entire structure for supporting the upper rail 9 is enhanced by the provision of a plurality of braces 20, 21, and 22, which extend from the upper horizontal portions to the uprights 14, 15, and 16 in vertical direction to the platform 5, so as to provide additional posts for the upper horizontal arms of these rail supports. 80

The two central rails 10 and 11 are secured to these braces 20, 21, and 22 and also to the end posts 7 and 8. The support of these rails on the intermediate braces 20, 21, and 22 is effected by suitable holders or brackets, shown in detail in Figs. 7 and 8. Each of the brackets consists of two side plates 23, suitably recessed to receive, when placed face to face with the companion plate, the web and foot portion of the rails 10 and 11, which rails may be supported therein by bolts passing through the openings 28, 29, 30, and 31; the two plates 23 of each bracket are held together and are fastened to the uprights 14, 15, 16 and braces 20, 21, by bolts 24 inserted through openings 25 in both of these plates. Spacing pipes or sleeves 26 and 27, shown in Fig. 3, serve for maintaining the brackets 23 at a suitable distance horizontally from the braces 21 and from the inclined portions of the uprights 14, 15, and 16 respectively. 95 The lengths of the sleeves 26 are selected so as to bring the rails 10 and 11 held by the brackets into one vertical plane with the parallel rails 9 and 12, the first named one being secured to the top portion of the structure, while the second named rail 12 is fastened to the top surface of the horizontal platform 5. 100

The rails 9 to 12 serve as guiding and supporting means for retaining devices or trucks 32 and 33. These retaining devices comprise the wheels 34, 35, 36, and 37, which have flanges similar to those of the ordinary car wheels. From Figs. 4 and 5 it will be seen that the upper pair of wheels 34 and 35 is disposed between plates 38 and 39, while the lower pair 36 and 37 is held between the plates 40 and 41. The axles 42 and 43 for the upper pair of wheels, therefore, extend through the side plates 38 and 39 and through the wheels located between these plates, while the axles 44 and 45 for the lower wheels 36 and 37 project through the side plates 40 and 41 and through the wheels which are held between these plates. 110 120 125 130

- The upper structure, including a pair of wheels and a pair of side plates, is connected with the lower structure, composed of similar elements, by means of cross braces 46 and 47, fastened to the outer surface of the side plates 38 and 40, and through the ends of which the various axles 42, 43, 44, and 45 also project. The rigidity of the structure is furthermore enhanced by the provision of
- 5 a vertical brace 48, placed on top of the cross braces 46 and 47, and which connects the outer side plates 38 and 40, this brace 48 being secured near its center to the intersecting portions of the diagonal braces 46 and 47. This upright brace 48 also carries near its center an eye or loop 49 for the attachment of a chain 50, the free end of which is provided with an articulated hook 51.
- 10 The details of this articulated hook are illustrated in Figs. 6 and 9. It consists of a bent shank having near one end an eye, through which the last link of the chain 50 is inserted, and having at the other end 15 a pivot 54 projecting through a slotted terminal portion 55 of this shank. The slotted end serves for the reception of the movable member 53 of this articulated hook, which may swing about the pivot 54 and 20 which is of flat cross section to project through a slot 56 in the shank 52 of the hook. An opening 57 near the free end 25 of this movable member 53 serves for the reception of a pin 58 having an enlarged head, 30 as shown in Fig. 6, whereby after the insertion of the pin through this movable member 53 a return movement of the movable member 53 through the slot in the shank 52 is prevented.
- 35 From Figs. 4 and 5 it will also be seen that the upper side plates 38 and 39 of the retaining devices or trucks 32 and 33 are provided with extensions 59, 60 and 61, 62 respectively, which project upwardly so as 40 to be located adjacent the sides of the head of the rail 9, to form an additional safeguard against lateral movement of the upper structure with respect to the rails. This additional safeguard, however, is not absolutely necessary.
- 45 The side plate 39 of the rearmost truck 33 has an eye hook 63, to which a chain 64 is attached. The other end of this chain is secured on a drum 65, which is supported on 50 the upright post 7 near the entrance end of the unloading portion of the platform. By means of a crank 66 connected with the drum 65 the chain 64 may be wound on the drum 65.
- 55 The operation of the device will be about as follows:
- 60 The apparatus is installed adjacent to the spur track or some other switch track leading from the main road to the establishment or plant. The unloading portion of the
- platform 1 is located with its lower end in opposition to a conveyer platform or some other suitable conveyer device, diagrammatically indicated at 67 in Fig. 3. This conveying device serves for transporting the 70 goods discharged from the car 68 to that part of the plant in which the material is to be used. The same mechanism or tractor which operates the conveyer 67 may also be used for gradually pulling, by means of 75 suitable chains or the like, the car 68 from the level track (not shown) over the entrance grade of the platform 1 to the unloading portion having the angle of discharge, the chain 50 of the retaining device having been attached by means of the articulated hook 51 to an eye 69 on the side of the car, as soon as this car has assumed an angle which will facilitate the unloading 80 of the same. After the attachment of 85 the first truck 32 to the car 68, the second truck 33 will also be connected with the car in the same manner, as soon as the car is in opposition to the second truck. The car is then fully advanced to the main or 90 unloading portion of the platform 1, and when the car has reached this unloading portion, the angle of which has been determined in accordance with the nature of the load mainly carried to the establishment, 95 the doors can be opened and the unloading operation can be begun.
- 98 After the completion of this operation the empty car is moved over the descending portion of the inclined surface 1 to the 100 point, where this surface again merges into the level of the ordinary track, and the hooks 51 are then unfastened from the eye bolts 69. In this movement of the car to the end of the platform the retaining devices 105 32 and 33 are also advanced in this direction, and a return toward the entrance end of the inclined platform may be effected by operation of the crank 66, whereby the chain 64 is wound on the drum 65. As this 110 chain is attached to the second one of the trucks, it is obvious that the first one will be pushed in direction toward the drum by the rear truck 33. Shock absorbing bolsters 70 and 71 may be secured to the uprights 115 7 and 8 at the end of the horizontal platform 5.
- I claim:
1. A trolley device for maintaining cars in unloading position on a dumping platform, comprising a plurality of parallel horizontal rails arranged in pairs, the rails in each pair being superposed with respect to each other and the pairs also being superposed with respect to each other, and a 120 retaining device movably carried on said rails and detachably connected with the car to be unloaded.
- 125 2. A trolley device for maintaining cars in unloading position on a dumping plat-

form, including two superposed pairs of rails, a truck provided with wheels, some of the wheels of the truck being in permanent engagement with the rails of the upper pair, and others of the truck being in permanent engagement with the rails of the lower pair, and means for connecting the truck with the car to be unloaded on the dumping platform.

10 3. A trolley device for maintaining cars in inclined position on an unloading platform, including a plurality of rails spaced vertically from each other and supported horizontally in parallel relation to the top edge 15 of the unloading platform, a pair of posts supporting the ends of said rails, intermediary posts, brackets secured to said intermediary posts, said brackets holding said rails intermediate the ends thereof, a truck 20 movably carried by said rails, and flexible connections between said truck and the car to be unloaded on said platform.

4. A trolley device for retaining cars in unloading position on an inclined platform, 25 including a plurality of rails parallel to each other and arranged in pairs, posts supporting the ends of said rails, additional posts, brackets carried by said additional posts, each of said brackets being adapted to 30 support a pair of rails in superposition,

the upper rail having the head directed upwardly and the lower rail having the head directed downwardly, trucks movably mounted on said rails, and flexible connections for holding the cars to be unloaded attached to said trucks. 35

5. A trolley device for retaining cars in unloading position on an inclined platform, comprising a pair of superposed trucks, each truck having a plurality of wheels, side plates on each side of said wheels and connecting the wheels of each truck, elements located in a plane different from the plane of said wheels and said side plates for connecting the trucks of each retaining device, 40 and flexible connections attached to the connecting elements. 45

6. In combination with a horizontal platform, a plurality of horizontal rails mounted in superposition on said horizontal platform and extending parallel to each other, retaining trucks movably carried by said rails, flexible connections secured to said trucks, and means mounted on one end of said platform for pulling said retaining trucks from one end of the platform toward the other end of the same. 50 55

In testimony whereof I affix my signature.

JOAQUIN FERNANDEZ SILVA.

Copies of this patent may be obtained for five cents each, by addressing the "Commissioner of Patents, Washington, D. C."
